SANITARY BOTTLE SPIGOT

Stanley Nellson, New York, N. Y.

Continuation of application Serial No. 541,790,
June 23, 1944. This application December 12,
1946, Serial No. 715,665

1 Claim. (Cl. 222—484)

1

This invention relates to new and useful improvements in a bottle spigot.

This is a continuation of my former application, filed on June 23, 1944, Serial Number 541,790, which has been abandoned.

More specifically, the present invention proposes the construction of a spigot for a Thermos bottle or other container, characterized by having a spigot mechanism of novel construction for quickly filling and discharging the container.

Still further it is proposed to provide a spigot for a Thermos bottle as aforesaid in which the spigot is provided with a valve.

Still another object of the invention proposes a spigot for a Thermos bottle as aforesaid in which the spigot and valve mechanism can be removed from the container of the bottle for cleaning and repair.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a side elevation of a sanitary bottle spigot constructed in accordance with this invention.

Fig. 2 is a perspective view of the spigot shown in Fig. 1.

Fig. 3 is an enlarged foreshortened inverted central view of the spigot and valve mechanism, parts being shown in full and associated parts of a Thermos bottle being indicated in dot and dash lines.

Fig. 4 is an inverted enlarged foreshortened perspective view of the valve.

Fig. 5 is an enlarged inverted foreshortened perspective view of a part of the spigot mechanism.

Fig. 6 is an enlarged side elevation of the top portion of the spigot mechanism.

Fig. 7 is an enlarged section on the line 7—7 of Fig. 3.

Fig. 8 is a view similar to Fig. 7 showing the spigot thumb piece and its push rod unlocked for disassembly.

Fig. 9 is an enlarged section on the line 9—9 of Fig. 1.

Fig. 10 is an enlarged section on the line 10—10 of Fig. 3.

The container is shown in the form of a Thermos bottle, which comprises the usual case 10 having a cap 11 screwed on the top thereof

2

and a two-walled vacuum glass container 12 therein.

The container is also provided with a spigot mechanism, indicated generally by the reference numeral 13. This mechanism includes a gasket 14 engaging the top of the container. A plate 15 engages the washer 14 by means of a flange 16, the plate 15 having a depressed cup 17 in the bottom wall of which is secured a spigot 20 in the upper end at which a conical valve seat 18 is formed, valve seat 18 opening into the container 12 and an orifice 19.

A spout 20 is secured to plate 15 and extends 15 away from the container 12 through the cover 23. A tube 21 is secured in the orifice 19, sealing the orifice. Tube 21 extends on one side of plate 15 almost to the bottom of container 12 and in the other direction extends just beyond cover plate 23. A conical seat 22 is formed in the bottom of the tube 21. A cover 23 having an orifice for the spout 20 and another orifice for the tube 21 rests on top of the flanges 16 and is engaged at its upper surface by a flange 24 formed on the cap 11. This cover 23 is formed of a material low in heat conductivity and forms a dead air space 20 between it and plate 15 which is effective as thermal insulation. Thus gasket 14, plate 15 and cover 23 are all removably secured to the case 10 and sealed to the container 12 by the cap 11. Cover 23 has an internal annular flange 25 centering it relative to the plate 15.

Two cylindrical spaced guides 26 are secured to the tube 21 by brackets 27, the guides 26 being 35 in line with the seat 18 and each is open through its entire side by means of a slot 28 as is best shown in Figs. 5 and 10.

A valve rod 29 is slidably disposed in guides 26 with its head 30 coacting with seat 18 and normally held in engagement therewith by a compression spring 31 engaging at one end the head 30 and at the other end the adjacent guide 26. The stem 32 of the valve is the same diameter as the slots 28 so that it may be slid through the 45 slots into the guides. It is held therein by two integral bushings 33 secured to rod 29 (Fig. 10) disposed in the guides 26. The bottom of the stem is bent at a right angle forming an operating arm 34 disposed over the end of the tube 21.

50 A push rod 35 is disposed in tube 21. It has a head 36 at its lower end having a conical face 39 in engagement with the seat 22 and an opposite conical portion 40 provided with a groove 41 in which is disposed the arm 34. The rod 35 is provided with a bushing 42 which is grooved for

air passage to the valve formed by the head 36 and the seat 22 and which is adjacent to the cover 23 for maintaining it centrally in the tube 21.

The upper end of the push rod 35 is connected to a disc 43 supported on a compression spring 44 in spaced relation from the top of the tube 21, disc 43 having a boss 45 and solder or the like securing one end of the spring, the other end of the spring being retained by the tube 21. The upper end of the rod 35 is provided with an annular groove in line with a slot 47 formed in the disc 43. A key 48 is disposed in the slot 47 and is pivotally secured thereto by a pin 49. The key 48 has a release edge 50, a part of the key 48 being circular and fitted with a depression 51' on its upper face fitting over rod 35 and a portion 52 of the key 48 extends beyond the disc 43 so that it can be engaged by a person's finger. The key 48 when it is in a position so that a portion of its curved edge 51' prevents rotation by engaging the side of groove 46 under pressure of spring 44 as shown in Fig. 7, secures the disc to the rod. However, it may be turned as shown in Fig. 8, whereupon the disc 43 and the rod 35 may be separated. A thumb piece 51 is secured to the disc 43 for providing a guard to prevent contact of one's fingers with the hot or cold spout tube 20, also to provide a one hand operation in discharging the contents of the bottle.

As gasket 14, plate 15 and cover 23 have no connection with each other, they may be lifted apart when the cap 11 has been unthreaded and disc 43 plus spring 44 removed from push rod 35 for cleaning and repair.

The operation of the device is as follows: To assemble the spigot, the rod 35 is disposed in tube 21. Cover 23 is placed on plate 15 and the assembly of disc 43 and spring 44 assembled on the end of rod 35 so that the spring 44 rests on cover 23 around the end of the tube 21. When the end of rod 35 reaches the bottom of the hole in disc 43, the locking key 48 is then turned to engage the locking depression 51 with rod 35. Then the valve is positioned in the guides 26 through the slots 28, the spring 31 being compressed sufficiently so that the arm 34 can be passed over the portion 40 and then let back until it is disposed in the slot 41. The spring 31 acts to keep the arm 34 in the slot 41 and the head 30 against its seat 18 except when it is desired to open the spout 20 for filling or discharging the bottle.

The gasket 14 is placed over the cup 17 of the plate 15 and the tube 21 and valve rod 29 are placed in the container 12 and all the parts are operatively secured together by the cap 11. In a similar manner in a reverse order, the spigot may be disassembled for cleaning or repair. No special tools or attaching devices are required for these operations.

The container may be filled through the top of the container before it is assembled or through

the spout 20 after the Thermos bottle and the spigot 13 are assembled. In the latter case the head 30 is separated from the seat 18 for filling the bottle by pushing the thumb piece 51 downward.

When it is desired to discharge the contents of the Thermos bottle, all that is necessary is to tip the bottle upside down and push the member 51 inward, pouring the contents out through the spigot 13. As the tube 21 extends to the vicinity of the bottom of the container, no liquid will run through the tube when the bottle is turned upside down as the bottom of the tube 21 will be out of the liquid before the push rod face 39 leaves the seat 22.

It is to be understood that this device may be used in any type of bottles or other containers for fluid.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A spigot for a container for liquids, comprising a gasket for engaging the top of a container, a plate disposed on top of said gasket and having a depressed cup extending into said gasket, said cup having a port and an orifice, a tube secured in said orifice and extending from opposite sides thereof and having a seat at its end disposed in said container, spaced guides secured to said tube in line with said port, each of said guides having a slot opening through its entire side, a push rod disposed in said tube having a head engaging said seat and a portion extending above said tube, a spout secured to said cup over said port on the side thereof remote from said container, a cover disposed on said plate having an orifice through which said spout extends and another orifice through which said tube extends, a thumb piece secured to said end of said rod above said tube, a spring compressed between said thumb piece and cover normally holding said head against said seat, a valve having a stem disposed in said guides, a head coacting with said port and an arm coacting with the bottom of said push rod, said stem having a diameter equal to said guide slots and a bushing secured to said push rod in each one of said guides holding said stem therein but permitting removal of said stem therefrom by lifting said stem to lift said bushings up from the correlated guide slot, a spring compressed between said head and the adjacent one of said guides for urging said valve head against said port, and a cap having a portion engaging said cover for holding said gasket, plate and cover on a container.

STANLEY NELLSON.
